THERMIONIC TUBE AND CIRCUITS

Clarence W. Hansell, Port Jefferson, N. Y., assignor to Radio Corporation of America, a corporation of Delaware

Application January 14, 1936, Serial No. 59,054

52 Claims. (Cl. 250—27)

This invention relates broadly to a new and improved thermionic tube of the cathode ray type and to new circuits for generating, rectifying, relaying, amplifying, frequency multiplying, demodulating or modulating alternating currents of any frequency.

A specific object of the present invention is to provide a new tube of the type described which is particularly adapted to generate, relay, amplify or frequency multiply or demodulate or modulate or convert from one frequency to another modulated or unmodulated ultra high frequency currents and to perform substantially all other services for which known thermionic tubes may be used. In addition my new tube makes possible the performance of other functions for which previously known tubes are unsuitable.

A further object of the present invention is to provide new and improved circuits for use with tubes of the type described in the preceding paragraphs when operating at ultra high frequency.

In general, tubes known heretofore are limited in their application in various respects. They have definite upper frequency limitations at which the inter-electrode capacity in effect provides a low reactance shunt across the impedance between the elements thereby preventing the building up of substantial potential difference between the cathode and grid or anode and grid. Moreover at ultra high frequency the grid potential reverses in a time period less than the time required for the electrons to travel from the cathode to the grid. Consequently the tube is substantially limited to frequencies, the half periods of which are greater than the time it takes for the electrons to travel from the cathode to the control grid.

Tubes of the cathode ray type have been known heretofore in the art. Moreover such tubes have been known in which steps have been taken to overcome some of the difficulties mentioned above. See, for example, Hansell U. S. Patent #1,938,331 issued December 5, 1933. In a particular application the electron stream has been deflected laterally and thereby caused to impinge to a varying extent on one or more suitably positioned anodes. Thus the action of the tube does not depend on the rate of flow of the electrons from the cathode to the control grid. However, in this latter tube low efficiency in operation of the cathode results from the nature of the cathode and its arrangement with respect to the other electrodes. In such tubes a rather small percentage of the electron emission is used in producing useful output from the tube. This

latter defect is in general present in nearly all other cathode ray type tubes known and represents one of the main disadvantages attendant on the use of such tubes.

An object of the present invention is to provide a new tube of the cathode ray type which is less limited as to frequency by the rate of flow of the electron stream from the cathode to the control grid.

Another object of the present invention is to provide a new and improved tube of the cathode ray type as described in the preceding paragraph in which the electrodes are arranged in a novel manner to obtain the utmost use of the electron stream. In this manner, high efficiency and high electron current are obtained.

The novel features of my tube and of various circuits in which said tube may be utilized have been pointed out with particularity in the claims appended to this specification.

The nature of my novel tube and the mode of operation of the same and of the circuits connected therewith will be better understood by the following detailed description and therefrom when read in connection with the drawings through which like reference characters indicate like parts and in which

Figures 1, 2, 4 and 5 show, for purposes of illustration, various modifications of my novel tube structure;

Figure 3 illustrates by curves the operation of the tubes of my invention;

Figures 6 to 12 inclusive illustrate novel circuit arrangements by means of which the novel tubes of the preceding figures may be utilized to relay, or frequency multiply alternating current potentials or direct current pulsations;

Figure 12a illustrates a circuit arrangement wherein the novel tube of my invention is connected in a novel circuit and coupled to a source of oscillations to produce oscillations of increased frequency;

Figures 13 to 17, inclusive, disclose novel circuits for utilizing my novel tube to demodulate oscillations. The oscillations may carry signals and may be of any frequency. The demodulation may be accomplished by a simple rectifying action or by the use of local oscillations for heterodyning purposes;

Figures 18 to 23 illustrate the use of my novel tube in novel circuits arranged to produce sustained oscillations of considerable amplitude and substantially constant frequency.

In Figures 18 to 23, inclusive, regeneration is

produced between the anode circuit and the accelerating electrode circuit.

In Figure 23, the frequency of the oscillations produced is controlled by means of a resonant, 5 low power factor line;

Figures 24 to 29, inclusive, illustrate the use of my novel tube in novel modulation circuits;

Figure 30 illustrates the manner in which the 10 novel tubes of my invention may be connected in novel phase modulation circuits;

Figure 31 illustrates diagrammatically a novel tone converter circuit utilizing the novel tubes of my invention;

Figure 31a shows diagrammatically a keying 15 circuit wherein keyed tone signals are converted into impulses which in turn modulate the oscillator for signalling purposes;

Figure 32 illustrates diagrammatically the essential elements of a novel transmitter circuit, 20 incorporating the tubes of my invention; while

Figure 33 shows diagrammatically a novel circuit arrangement wherein a thermionic tube of the present invention controls the amplitude of a radio frequency amplifier in a novel fashion in 25 accordance with the intensity of signals characteristic of the signals impressed on the amplifier.

Referring to the drawings and in particular to Fig. 1 thereof, 2 is a low voltage high current 30 cathode axially located with respect to an accelerating and control electrode 4 which as shown has an inner-periphery relatively close to one end of the cathode 2 and an outer periphery which is relatively widely spaced from the cathode 2. The intermediate portions of the accelerating and control electrode 4 recede from the cathode as shown from the inner-periphery to the outer periphery thereof. The cathode 2 is supplied as shown with heavy heating current 40 through heavy leads L coaxially with the cathode which may be connected as shown to a source of cathode heating current. The anode 6 is located coaxially with respect to the heating leads of the cathode and is separated from the electron emitting portion of the cathode by a disk-shaped portion 7 arranged as shown. The anode may be maintained at the desired direct current potential by connecting the same as shown to the positive terminal of a source of potential.

50 The arrangement as shown causes electrons leaving different points along the cathode to be accelerated at different rates by the control electrode 4 and to acquire different velocities in their travel from the cathode toward the anode. 55 Those leaving the end of the cathode near A acquire a higher velocity than those leaving the cathode near the point B. The velocity which may be imparted to the electrons may decrease progressively from the point A to the point B 60 and may decrease at various rates as desired by properly shaping the accelerating electrode 4.

Due to the large cathode current, which should be derived from a constant direct current source, 65 a magnetic field exists around the cathode and its end connections. This magnetic field deflects the electrons drawn out from the cathode toward the anode, if the cathode current is in the correct direction. Those electrons having high velocity travel a relatively long path in the magnetic field, while those having a low velocity, 70 travel a relatively short path. As a result when the tube is arranged in accordance with my invention, all electrons leaving the cathode at one instant strike the cathode stem 7 or the anode 75 6 at substantially the same later instant. More-

over, in the arrangements shown all electrons leaving from different points along the cathode between points A and B tend to strike the cathode stem at the right of B, or the anode, at the same instant. In other words, in my novel tube there 5 is a strong focussing of the electron stream on a ring enclosing the cathode lead, which may be selected at will. The location of the ring on which the electrons are focussed is a function of the intensity of the electron stream, the potential 10 of the anode, and of the energizing and shaping of the electrodes, and in particular of the accelerating control electrode 4.

The electron flow has been indicated diagrammatically by the shaded areas in Fig. 1. These 15 areas in particular indicate the outside limits of the electron path in their passage from cathode to anode or from cathode to the cathode stem. The shaded areas 10 which come to sharp points on the anode are intended to show a cross section 20 of the volume occupied by moving electrons when the anode current is a maximum. This condition is attained principally by applying a predetermined potential between 2 and 4. The overlapping shaded areas 12 which come to sharp 25 points on the shield 7 on the cathode stem are intended to show a cross-section of the volume occupied by moving electrons when the anode current is zero. This condition is attained when the potential on 4 is made less positive relative 30 to 2.

By varying the potential between the accelerating control electrode 4 and the cathode 2, the position at which the electrons strike the anode or return to the cathode stem or to the shield 35 7 on the cathode stem may be varied. Therefore, the current flow to the anode may be controlled by simply varying the potential between the control electrode and cathode or by varying the anode potential or both. It may also be controlled by varying the cathode current in any manner to vary the magnetic field but in the present application I prefer to use variation in electric forces instead.

By adding annular shields 7 and 14 to the 45 cathode stem as shown in Fig. 1 on each side of the anode, the electrons may be shielded from the electric field of the charged anode during most of their flying time and variations in anode potential will have little effect upon the anode current. 50 This results in a high anode impedance similar to that of shield grid tubes of the type already known in the art and gives a high amplification constant without requiring flow of current to the control electrode during peaks of 55 anode current.

Obviously the electron current may also be made to fall upon the shield 14 by making the potential of 4 sufficiently positive with respect to 2. By making adjustments for varying the electron current between shield 14 and anode 6 the alternating current polarity of the tube output is reversed to what it would be when the electron current is varied between shield 7 and the anode.

My novel cathode ray tube may take many forms. 65 For example, the tube may be arranged as indicated in Fig. 2. In Fig. 2, one end of the cathode terminates in a conductive disk 9 as shown. The disk 9 serves not only to supply heating current to the cathode but also as a shield between two 70 chambers within the tube envelope. One chamber includes the input electrodes which are to be connected to the input circuits, while the other chamber includes the output electrodes which are to be connected to the output circuits. This, of 75

course, increases the stability of operation of the tube particularly when it is operated at high frequencies at which shielding between output and input circuits is desirable. Moreover, in Fig. 2 the anode 6 has a U-shaped cross section as shown. This reduces or eliminates flow of current from anode 6 to electrode 9 due to secondary emission from the anode when, in operation the anode potential may be negative with respect to electrode 9 during portions of the operating time.

It should be noted in connection with the arrangements shown in Figs. 1 and 2 that by adjusting the control electrode potential above or below that required to give maximum anode current we may reverse the polarity of the alternating current output with respect to the alternating current input potential and current. This feature is not possessed by ordinary tubes, though need for it is often met with in keying and signalling circuits. As an example, we may convert from single circuit to pushpull circuit amplification, detection, etc., by feeding the inputs of two of the tubes in parallel while connecting their outputs in pushpull, provided we have the action reversed in the two tubes.

The principles of my new type vacuum tube may very well be applied to providing more efficient cathodes for all sorts of cathode ray tubes, including those in which the brightness of the spot is modulated in addition to the spot being moved over a fluorescent screen (kinescope tubes). They may also be applied to television transmitting tubes such as Dr. Zworykin's "Iconoscope".

To obtain some idea as to the correct dimensions to use in a tube suitable for receiving purposes I will assume that the control electrode and anode are each maintained at a positive direct current potential of about 135 volts with respect to the cathode. The effective diameter of the control electrode and twice the maximum distance electrons are to travel out from the axis of the cathode will be assumed to be .3" or 300 mils.

Then, for an approximate equation take Hull's equation I on page 915 of Transactions A. I. E. E., Vol. XLII, 1933, which is:

$$E = 0.0188I^2(\log_{10} D/d)^2$$

where

50 E=voltage.

I=cathode current in amperes.

D=diameter of anode (in this case effective diameter of accelerating and control electrode).

55 d=diameter of cathode.

Substituting in this equation we get:

$$135 = 0.0188I^2(\log_{10} 0.3/d)^2$$

or better yet use Hull's Equation 2, which assumes 60 a cathode temperature of 2500° K., then:

$$E = 0.000716d^3 \text{ mils}(\log_{10} D/d)^2 \text{ or}$$

$$E = 0.000716d^3(\log_{10} 300/d)^2$$

The values of E for various assumed values of d 65 become

<i>d</i>	<i>E</i>
Mils	Volts
3	0.0774
30	19.35
60	75.5
90	143.
150	218.

The values have been plotted in Fig. 3 and indicate that a cathode diameter of about 86 mils

would be required for a control electrode having an effective diameter of about 0.3 inch.

If we assume D=0.6 inch then the control electrode voltage for various cathode diameters will be:

<i>d</i>	<i>E</i>
Mils	Volts
30	32.8
40	63.4
50	104
60	155
70	216
90	354

10

In this case a cathode diameter of 57 mils would 15 be about right.

It is noted that plain tungsten filaments, of the sizes required for operation at 135 volts on the control electrode, will require filament currents of the same order of magnitude as we use on water cooled tubes.

If a tube is arranged in accordance with my invention and includes a 40 mil filament having an active length of .5 inch in combination with a control electrode of 1 inch effective diameter, 25 we would obtain in the ideal case a peak anode current of .5 ampere and in doing so we would use a direct current control electrode potential of 90 volts. With 90 volts on the anode we might obtain a maximum alternating current output of 30 about 2.5 watts. By raising the anode potential we should obtain about 25 watts at 900 volts and 250 watts at 9000 volts. The filament power required would be about 100 watts. The power and voltage gain obtainable will be very high in my 35 new tube.

Since very heavy cathode current is objectionable in receiving tubes other means in addition to those shown in Fig. 2 for focussing the electron stream on the anode or target besides the 40 magnetic field is desirable. Such a focussing and electron timing scheme has been shown in Fig. 4. In this figure the tube comprises a control electrode 4 and indirectly heated cathode 2 having a radially enlarged shielding portion 5 as shown. The cathode 2 and control electrode 4 are separated from the anode by a shield and accelerating electrode 9. Annular openings are provided in the shield 9 to permit the electron stream, when properly focussed, to reach the anode 6. The anode 6 is, as in Fig. 2, U-shaped in cross section. This shaping of the anode minimizes the effect of secondary emission by reducing the possibility of potential gradients where secondary emission is produced by primary electron impacts upon the anode surface and so preventing the secondary emission produced from reaching the other electrodes. The diaphragm electrode 9 is preferably charged to a more positive potential 50 than the accelerating and control electrode 4. Preferably the diaphragm 9 is brought outside the glass envelope of the tube as shown to provide a continuation of the metal partition between the two shielded compartments in the tube. The continuation of the diaphragm 9 may also serve 55 as the mounting for the tube upon the metallic shield 18, which effectively isolates the input circuits from energy feed back from the output circuit.

In the operation of the tube electrons leaving the filament are first acted on chiefly by an electric field due to the control electrode 4. The force is greatest on electrons leaving the cathode from 60 points farthest from the anode. This is due to the shield on the end of the cathode and the size, 65 70 75

shape, spacing and potentials of the other electrodes. After the electrons leave the cathode they come more and more under the influence of the electric field produced by the diaphragm electrode potential and this bends the electron paths in approximately the same way as the magnetic field in the tubes of Figs. 1 and 2. I so arrange, shape and energize the electrodes that all electrons leaving the cathode arrive at the diaphragm electrode 9 at nearly the same radial distance from the axis of the tube. Moreover, the electrons leaving the cathode at the same instant arrive at the diaphragm at nearly the same later instant and consequently are concentrated on the anode at the same instant.

The areas 16, enclosed by the dotted lines, in Fig. 4 represent the electron paths for the condition of maximum anode current. For other control electrode potentials than that assumed in Fig. 4 the electrons would miss the openings in the shield 9, which also acts as an accelerating electrode, partially or altogether and so reduce the anode current to any desired value between maximum and minimum.

By varying some of the electrode potentials the distance from the axis of the tube at which the electrons arrive at the diaphragm electrode 9 may be varied. Consequently the electrons may be made to strike either the diaphragm 9 or the openings in it accordingly to the electrode potentials. If they strike the openings they will, of course, land on the anode and produce an anode current. Consequently we may control the anode current by varying the control electrode or cathode potential with respect to the diaphragm, or we may vary both. I prefer to vary only the control electrode potential in most cases.

In Fig. 4 I have shown openings in the diaphragm 9 of considerable axial length so that there will be little potential gradient inside these openings. This reduces the forces acting on secondary emission electrons and reduces the secondary emission from the diaphragm which can arrive at the anode.

Of course, my novel tube is applicable to all classes of signalling including transmitting as well as receiving. Where large powers are to be handled I contemplate cooling one or more of the electrodes of the tube. For example, as shown in Fig. 5 the anode electrode 6 of the tube may be cooled by a circulating fluid. The cathode 1 is somewhat similar to the cathode 2 of Figs. 1 and 2. Here, however, the cathode terminates in a radially expanded portion 5 which is continued axially as shown at 5' to form a shield for the cathode 2 and for the accelerating electrode 4. This axial portion 5' may also serve as one of the leads L' for applying the heating current to the cathode. The radial portion of the shield has openings therein through which the electrons may reach the anode 6. The magnetic field from the cathode current deflects the electrons as in the tubes of Figs. 1 and 2. The dotted lines in the upper half of Fig. 5 show the condition of maximum anode current while those in the lower half show a condition of zero anode current. Another condition of zero anode current can be obtained by increasing the positive control electrode potential to make the electrons strike outside the openings in 5.

The tube of Fig. 5 may, of course, normally be used with a fluid cooled output circuit inductance or coil of copper tubing through which water may be circulated to the anode as disclosed in Moser,

U. S. Patent #1,857,029, May 3, 1932. See also Hallborg's U. S. Patent #1,963,131, June 19, 1934. Although I have shown an anode made of metallic tubing with a cylindrical cross section area it will be understood that the tube may have other shapes. If the tubing has a disk shape or U-shaped cross section such that the electrodes strike the anode in a depressed area as they do in Figs. 2 and 4 secondary emission will be reduced and the effect of that which takes place will be reduced.

Since to obtain high efficiency in any of the tubes in the foregoing figures as an oscillator or class C amplifier, we must drive the anode potential down almost to zero when anode current flows, we must provide for the condition where the anode potential is below the diaphragm potential. This requires suppressing the effect of secondary emission from the anode. The anode in my tube is so shaped as to give very low potential gradient where the initial electrons strike. This reduces the secondary emission current which can flow back from anode to diaphragm. Preferably a carbonized anode, or anode of material selected to minimize secondary emission, is used.

The tubes of the present invention may be utilized for any purpose for which any known types of vacuum tubes can be used and, in addition will perform functions for which other known types of tubes are unsuitable.

When it is desired to relay or amplify alternating current potentials or direct current impulses of any frequency, with circuits similar to those shown in Fig. 1, the said impulses may be applied to the leads marked "input", connected to the primary winding of a transformer 38, the secondary winding of which is coupled as shown between the control and accelerating electrode 4 and the cathode 2. The last named connection may, if desired, be by way of a by-passing condenser C. The secondary winding of the transformer may be tuned to the frequency of the oscillations or impulses to be relayed if desired by a variable condenser 31 connected as shown. The relayed and amplified oscillations impressed on the input electrodes are repeated in the tube in the manner described hereinbefore and caused to appear on the anode electrode from which they may be set up in an output circuit including a primary winding connected as shown between the anode 6 and the cathode 2 by way of a second by-passing condenser C. This primary winding of transformer 32 may be tuned by a variable condenser 33 connected as shown. The oscillations appearing in this tuned circuit may be impressed on the secondary winding coupled thereto and transferred from said winding to any utilization circuit by way of the leads marked "output".

The anode electrode may be connected as shown to a positive point on a source of direct current potential, the negative terminal of which is connected to ground and to the cathode. The control electrode and accelerating electrode 4 may be maintained at the desired potential with respect to the cathode by connecting electrode 4 to a separate source of potential or to the desired point on the first named source. The sources of potential may be a battery or a filter network connected with a rectifier.

In the description of the novel circuits in which my novel tube operates, which follows, the tube has been shown somewhat schematically.

The tube of each of the circuits may be the tube shown in Figs. 2, 4 or 5.

Many other circuits may be utilized with the novel tube of my invention. For example, as shown in Fig. 6, the potentials to be amplified may be impressed on the primary winding of a transformer 30, the secondary winding of which is connected as shown to the control and accelerating electrode 4 and by way of a potentiometer resistance 34 to the electrical center of the cathode heating circuit. If the cathode is insulated from the cathode heater, as is done in some known types of tubes, the connection will be to the cathode rather than to the center of the heating circuit. The cathode heating circuit here is assumed to be connected with an alternating current source of potential and the cathode may be of the directly or indirectly heated type. The accelerating and shield electrode 9 may be connected as shown to a point on the potentiometer resistance 34. The anode electrode is connected by way of the primary winding of a transformer 32 to an additional point on the potentiometer resistance 34. The oscillations or impulses to be amplified are shunted around the source and across resistance 34 by way of by-pass condensers C, C' and C'' connected as shown between the cathode and the various leads between the other electrodes of the tube and the potentiometer resistance 34. To reduce voltage variations the potentiometer may be made up of material having self-regulating resistance, such as Thyrite, or of series connected glow discharge voltage regulating tubes or similar devices. See my U. S. application Serial No. 710,235, filed February 8, 1934, now Patent #2,086,910 dated July 13, 1937.

In operation, the electrons are concentrated on the shield 9 or the openings therein. As the potential on 4 swings due to the varying potentials from 30, the distance from the axis at which the electrons impinge on 9 swings radially. The anode current flow waxes and wanes directly or in a reverse sense at the frequency of the applied potentials. Whether the anode current follows the applied current or is reversed with respect thereto depends on the magnitude of the direct current potential between 2 and 4 and between 2 and 9.

In Fig. 6 it has been assumed that low frequency impulses or alternating currents are to be amplified and iron- or alloy-cored transformers have accordingly been shown. Of course, where higher frequencies are involved the transformers may be air-cored and the windings thereof may be tuned to resonance at said frequencies where desired.

The input circuits of the amplifier of Fig. 7 are somewhat similar to the input circuits of the amplifier of Fig. 6. The emission and control of said emission is similar to that of the tube and circuit of Fig. 6. However, in Fig. 7 the shielding and accelerating electrode 9 serves as the anode electrode connected with the output transformer 32, while the anode electrode 6 is maintained at a less positive potential and is connected as shown to a point on the potentiometer resistance 34. In this arrangement the fluctuations of the shield potential resulting from the amplifying action may be made to add to the amplifying action of the tube or to oppose the same depending upon the adjustments of electrode potentials. The tube and circuits are regenerative when a change in shield potential will change the shield current in a direction

to increase the change in potential. The regeneration may be carried to a point at which sustained oscillations are produced. The amount of regeneration may be controlled by controlling both the potential adjustments and the losses in the circuits, or by introducing and varying a coupling between output and input circuits.

In the arrangement of Fig. 8 the anode electrode 6 and the shielding and accelerating electrode 9 both serve as output electrodes. Here, as in Fig. 7, the fluctuations in potential of the accelerating shield electrode 9 may be used to cause a regenerative effect and to add to the fluctuations of the anode potential or the potential fluctuations of 9 and 6 may be made to oppose each other to the desired extent. The opposing effects may be equal or may produce degeneration or regeneration to such an extent as to produce oscillations at almost any frequency. Here again it is assumed that low frequency oscillations or impulses are to be amplified with the specific arrangement shown. The circuit is, of course, applicable to the handling of high frequency oscillations. In the latter case air-cored tuned transformers may be utilized where desired.

An arrangement for amplifying or frequency multiplying high frequency oscillations is shown in Fig. 9. The circuit arrangement of Fig. 9 except for the air-cored transformers 30 and 32, tuning condenser 37 and the tuned output circuit 39, is somewhat similar in arrangement and operation to the circuit of Fig. 6. In Fig. 9, however, the output energy is supplied from a point on the inductance in the output circuit 35 to any load circuit by way of a coupling condenser 36.

The push-pull arrangement of Fig. 10 comprises a radio frequency push-pull input circuit transformer 30 including a primary winding 40 which may be connected to the source of oscillations to be amplified and a secondary winding connected as shown at its terminals to the electrodes 4 and at a point intermediate its terminals to ground and from ground to the cathode or to the electrical center of the tube cathode heating circuits. The anode electrodes are connected as shown in push-pull relation by way of a tuned circuit 39, a point on the inductance of which may be connected by way of a blocking condenser 36 to a utilization circuit. The shielding and accelerating electrodes 9 may be maintained at the desired potentials. This circuit may be used either as a push-pull amplifier or as a frequency multiplier for producing odd harmonic multiplication. In the former case the secondary winding of the transformer 30 and the tuned circuit 32 are tuned to the fundamental frequency while in the latter case said winding and circuit are tuned to the fundamental and the odd harmonic to be selected respectively.

In the arrangement of Fig. 11 oscillations from the source to be amplified are applied as shown between a capacity 38 and ground. The free terminal of the capacity 38 is connected as shown to a point on the inductance of circuit 40. The inductance is shunted by a tuning condenser 31. One terminal of the inductance is connected as shown to both accelerating and control grids 4 while the other terminal of the inductance of circuit 40 is connected to a point on the potentiometer resistance 34. The electrodes 9 are grounded for radio frequency potentials by C'' while the anodes are connected in push-pull by circuit 39. The circuit as shown may be used as

an amplifier and also for converting from a single-ended circuit to a push-pull or double-ended circuit when the electrode potentials are suitably adjusted. To accomplish this the oscillations 5 are applied as shown in parallel between the control grids and the cathode of each tube. The anode circuit is connected in push-pull relation as shown between the anodes of the tubes. The input may be connected to a single stage and the 10 output to a push-pull stage. The oscillations from the anode circuit are supplied by way of a pair of coupling capacities 36 and 36' as shown. The circuits 40 and 39 are tuned to the frequency of the potentials to be amplified and converted. 15 This circuit may be utilized as an amplifier and frequency multiplier. In the latter case the anode circuit or output circuit 39 may be tuned to an even harmonic of the fundamental frequency to which the input circuit is tuned. Here, as in the 20 prior arrangements, the radio frequency paths may be completed by way of by-passing condensers C, C' and C'' connected as shown with the various circuits. These by-pass condensers provide low impedance paths around the energizing sources for the alternating currents or impulses to be handled.

In all of the amplifier and frequency multiplier circuits shown in Figs. 6 to 11 inclusive, the tubes may be adjusted to give amplification of 30 the types known in the art as class A, class B and class C. By suitable adjustments the tubes and circuits may be made to act as amplitude limiters in which the variation in power output is less rapid than the variation in power input.

35 In the arrangement shown in Fig. 12, it is assumed carrier frequency or higher oscillations or impulses are to be amplified or frequency multiplied or demodulated, depending upon the character of the output circuit. The output circuit 40 may provide regeneration or degeneration of the output energy. This regeneration or degeneration may be obtained by inserting a variable impedance 46 in the energizing circuit for the shielding and accelerating electrode 9. By tuning this 45 impedance or by varying the same the regeneration or degeneration may be selective. That is, it may apply to a particular portion of the frequency range impressed on the input circuit or produced in the tube and discriminate against the other 50 portions of the frequency range. When the device operates as a demodulator, the output circuit may include a by-pass condenser, indicated as X in the figure.

In Fig. 12a, I have shown diagrammatically a 55 frequency multiplying system wherein the thermionic tube of the present invention having its accelerating electrode and cathode 2 connected to a tuned circuit 40 coupled to a source of high frequency oscillations O. The anode 6 of this 60 tube is connected to tuned circuit 40' which is in turn coupled to an output circuit. A variable capacity VC is connected as shown between the anode-electrode 6 and accelerating electrode 4 to produce the necessary feedback. The anode 65 circuit 40' may be tuned to a harmonic of the oscillations 20. The oscillations of increased frequency may be supplied from the circuit 40' to any load circuit, as for example an antenna system A.

70 Here, as in the prior case, the oscillations to be amplified or demodulated may be shunted around the energizing source by way of by-passing condensers C, C' and C'', connected as shown between the low potential ends of the input and out-

put circuits and ground and from ground to the cathode of the tube.

Fig. 13 illustrates the use of my novel tube in a rectifying or detecting circuit. In this circuit, modulated high frequency oscillations are applied to the input circuit 40 including the tuning condenser 37 and are impressed from said circuit on the controlling and accelerating electrode 4 and filament 2. The electrodes including the accelerating electrode 4 are maintained at a potential such that rectification of the modulated wave is accomplished in the tube and the modulations on the wave appear in the output circuit including the transformer 32. Potentials at frequencies higher than the desired output frequencies will be 15 by-passed around the transformer 32 by condenser X, connected as shown.

In the arrangement in Fig. 14, the modulated high frequency wave is applied to the electrodes of the tube in the same manner that it is applied 20 in Fig. 13. Here, however, the shielding electrode 9 is connected in the output circuit so that the signal frequencies obtained by rectification in the tube appear in the transformer 32, connected with 9. In this modification, as in the modification 25 shown in Fig. 7, the input and output energy may be regenerated by applying the proper direct current potentials to the electrodes 9 and 6. Regeneration or degeneration may also be obtained or assisted by means of suitable impedances inserted in series with the connections to electrodes 30 6 and 9.

In the arrangement shown in Fig. 15, signal carrying waves from two sources or from a push-pull output stage, or signal carrying waves from 35 one source and beating oscillations from another source may be applied on the input circuit including the tuned condenser 37 and from said circuit to the controlling and accelerating electrode 4 for demodulating purposes. In this modification, the shielding electrode 9 and the anode 6 are both connected to the primary winding of the transformer 32 so that a push-pull output effect may be obtained. In this modification, as in the modification shown in Fig. 8, regeneration 40 45 of the signal or degeneration of the signal in the output circuit may be obtained by applying the correct biasing potentials to the electrodes in the tube and in particular to the electrodes 9 and 6 and by means of suitably inserted impedances. 50 In this modification, both halves of the primary winding of the transformer 32 may be by-passed by condensers X and X' connected as shown.

In the modification in Fig. 16, the signal modulated wave is applied to the controlling and accelerating electrode and cathode in the same manner in which they are applied in Figs. 13 and 55 14. In the arrangement of Fig. 16, however, high frequency regeneration or degeneration may be accomplished by connecting the output circuit in 60 series with an inductance 41 coupled as shown to the inductance in the input circuit 40. Regeneration may be carried to such an extent that the tube oscillates or to an extent sufficient to stop oscillations which would otherwise be 65 present or to increase amplification only, depending upon the character of the signal to be received and demodulated. Here, as in the arrangements of Figs. 12, 13 and 14, the input circuit 40 including the tuning condenser 37 may 70 be tuned to the frequency of the signal modulated wave to be demodulated.

In the demodulator circuit in Fig. 17, the screening electrode 9 is connected as shown to the cathode by way of an alternating current 75

circuit including a tuned reactive circuit 46 and the by-passing condenser C''. By tuning the circuit 46 in the appropriate manner, regeneration or degeneration on any desired input or output frequency may be insured. Moreover, regeneration may be carried to such an extent as to produce oscillations in the circuit 9, 46 for heterodyning with the incoming signal modulated wave to produce in the output circuit of the demodulator an intermediate frequency. In the latter case, the iron core transformer 32 may be replaced by a transformer or reactance, tuned by means of a condenser, which will operate efficiently at the intermediate frequencies.

15 In both Figs. 15 and 17 the two inputs may have a small difference in frequency in order that their combination may produce beats which can be detected or rectified in the tube to make the beat frequency audible. This is equivalent in results to the well known heterodyne detector for continuous waves. Alternatively the two inputs may have a difference in frequency above audibility in which case the beats will also be above audibility and correspond to the detection which 25 takes place in the first detector of a superheterodyne receiver.

When it is desired to generate oscillations, an arrangement as shown in Fig. 18 may be utilized. Here, the filament may be heated by a circuit connected as shown in the preceding figures. A tuned oscillatory circuit 45 may be connected as shown between the controlling and accelerating electrode 4 and the electrical center of the filament heating circuit by way of ground and condenser C. The anode electrode 6 may be coupled to an inductance 47 variably coupled to the inductance in the tuned circuit 45. When proper potentials are applied to the electrodes 4, 9 and 6, sustained oscillations will be produced in the 40 tube and circuits 45, 47 and said oscillations may be supplied to any utilization circuit by way of a coupling condenser 48, connected as shown to the anode 6. High frequency oscillations appearing in the circuit 45 and in inductance 47 and 45 on the shielding electrode 9 may be by-passed around the potential sources by way of by-passing condensers C, C' and C'', connected as shown.

The oscillator shown in Fig. 19 is similar in many respects to the oscillator shown in Fig. 18. 50 In the oscillator of Fig. 19, however, a tuned anode circuit 49 is utilized and is variably coupled to an inductance 50 connected with the controlling and accelerating electrode 4.

In the oscillator of Fig. 20, a tuned oscillatory 55 circuit 45 is connected between the accelerating electrode 4 and the cathode 2 and a tuned oscillatory circuit 49 is connected between the anode and the cathode and coupled to the first named circuit, thus inductive feedback coupling is provided and oscillations may be produced with either polarity of feedback coupling provided suitable power supply potentials are applied to the tube.

60 Fig. 21 shows an oscillation generator with a tuned anode circuit 49, tuned accelerating electrode circuit 45, and either capacitive or conductive feedback coupling, depending upon the size of the capacity 52 in the feedback circuit. 65 Since the tube may be adjusted for either polarity of output with respect to input, by adjusting the bias on 4, and the tuned circuits 45, 49 may be either exactly tuned or detuned in either direction from the frequency of oscillation, I may 70 use either polarity of feedback. A switch S in 75

the feedback circuit is shown for reversing the feedback polarity.

Fig. 22 shows an oscillation generator with a tuned anode circuit 49 and tuned circuit 45 connected with the accelerating electrode 4, having 5 feedback through a piezo-electric quartz crystal PC for stabilizing the frequency. Undesired capacity feedback between the electrodes of the crystal holder may be neutralized by means of a neutralizing condenser NC connected as shown 10 between the high potential terminal of the crystal PC and a point on the tuned circuit 45. A shield 54 may be interposed between the anode and control electrode circuits, as shown, for the purpose of reducing the undesired feedback between these circuits.

Since the tube will operate to generate oscillations with either polarity of output relative to input, I may reverse the connections from the crystal and neutralizing condenser where they 20 tap on to the inductance in the accelerating electrode oscillation circuit 45.

The frequency of the oscillations generated by my novel tube and circuits may be stabilized as shown in Fig. 23, by a low power factor resonant 25 circuit or transmission line 60, points on which may be connected by way of movable taps to the tuned resonant circuit 45 connected with the accelerating electrode 4 and the tuned resonant circuit 49 connected with the anode electrode 6. 30 In this case, the polarity of the feedback may be reversed if desired by means of the reversing switch S. The resonant transmission line may be as disclosed in my U. S. application Serial No. 692,092, filed October 4, 1933 now Patent 35 #2,095,980 dated October 19, 1937. When the proper charging potentials are applied to the electrodes in the tube, oscillations are developed in the tubes and circuits and energy is transferred from the tuned resonant circuit 49 to the 40 low power factor circuit or line 60 and from the line to the tuned resonant circuit 45 to reinforce said oscillations and stabilize the frequency thereof. In a modification, the connections from the oscillatory circuits 46 and 49 may be made to the 45 same end of the resonant circuit or transmission line 60. In this case, the line may be made substantially one-quarter wave length long or any multiple of one-quarter wave length long, and then feedback of sufficient amplitude and correct 50 phase will only be obtained at the resonant frequency of the line. A resonant low power factor line for feedback and stabilizing purposes in an oscillatory generator has been disclosed in U. S. application Serial No. 692,092, Filed Oct. 4, 1933 55 now Patent #2,095,980 dated October 19, 1937.

When it is desired to modulate carrier wave oscillations, a circuit as illustrated in Fig. 24 may be utilized. In this arrangement, the high frequency waves to be modulated are applied by way 60 of the tuned circuit 45 between the accelerating electrode 4 and cathode 2. The modulating potentials may be supplied from any source by way of a modulation frequency transformer 50 connected as shown to the shielding and accelerating 65 electrode 9. The modulated high frequency wave will appear in the tuned circuit 49 connected with the anode 6 and may be supplied from said circuit by way of either an inductive coupling or a coupling condenser 48 to any utilization circuit. In 70 accomplishing modulation, regeneration or degeneration of the modulating energy may be accomplished by applying appropriate potentials to the electrodes and in particular to the screening electrode 9 and anode 6 and by placing suit- 75

able impedances in the connections to the electrodes.

In the modification shown in Fig. 25, the modulating potentials are applied by the transformer 50 to the anode circuit and the modulated high frequency wave may be supplied by the transformer 62 to any utilization circuit. Here, as in Fig. 24, high frequency oscillations may be bypassed around the power sources by way of bypassing condensers C, C' and C'' connected as shown.

In the modification of Fig. 26, the modulating potentials as well as the high frequency carrier wave are applied to the controlling and accelerating electrode 4. The modulated wave may be supplied from the anode circuit, as in Fig. 24.

In the modification shown in Fig. 27, the high frequency wave is applied between a point on the inductance in the tuned circuit 45 and ground 20 and from said circuit to the accelerating electrode 4 and cathode 2. The modulating potentials are supplied by way of the secondary winding of a transformer 50 between the screening electrode 9 and the anode 6. In this manner regeneration 25 at the frequency of the modulating potentials may be obtained by applying the proper potentials to the anode and screening electrode, thereby insuring a high input impedance into which the high frequency oscillations to be modulated 30 may work.

In some cases, it may be desired to produce and modulate oscillations by means of a single tube. In this case, a circuit arrangement as shown in Fig. 28 may be utilized. Here, the controlling 35 and accelerating electrode 4 and screening electrode 9 are connected in oscillation producing circuits including the tuned oscillatory circuit 69. The oscillations produced are modulated in the anode circuit and supplied from the anode 40 circuit by way of the transformer 62 to any utilization circuit. In order to prevent reaction of the anode and output circuit on the oscillation producing circuits, a neutralizing condenser 68 may be connected as shown between the anode 6 45 and a point on the tuned circuit 60.

When it is desired to receive transmitted signals of any character, I may utilize a receiving system as illustrated in Fig. 33. This system may comprise a receiving aerial 110 coupled to 50 an amplifier 112 which is in turn coupled to an amplifier 114. The output of the amplifier 114 may be connected to demodulate on detector 116 and the output of said detector may be coupled to a low frequency amplifier 118, the output of 55 which may be coupled to any utilization circuit, as for example telephones. In order to control the output of the receiver and maintain the same relatively constant, irrespective of swings in the amplitude of the received wave, I couple 60 the amplifier 114 to a tuned circuit 120 coupled between the accelerating electrode 4 and cathode of a thermionic tube. The anode electrode of the thermionic tube is connected as shown by way of a source 122 and a resistance 124 to the 65 cathode of the tube. The resistance 124 may be connected as shown by way of an automatic volume control line AVC to the accelerating electrode and cathode of one or more thermionic tubes in the amplifier 112, to thereby control the 70 gain of said amplifier tube in accordance with the potential drop in the resistance 124. The potential drop in the resistance 124 is in turn a function of the amplitude of the received signal. When the signal amplitude increases above normal, the gain of the amplifier 114 is reduced and 75

the opposite effect is produced by a decrease in the received signal amplitude. In practice the location of the source 122 may be changed or other anode circuits may be used.

The modification shown in Fig. 29 is similar to the oscillation generator of Fig. 28, except that a piezo-electric quartz crystal PC has been included in the circuit connected with 4. In parallel with the crystal PC is an impedance 64, which supplies direct current potential to the electrode 4. The crystal on proper adjustment of potentials and circuits will stabilize the frequency of the oscillations produced in the self-oscillation circuit including the electrodes 2, 4, 9, the piezo-electric crystal PC and the tuned circuit 60. Here, as in the modification of Fig. 28, the modulating potentials may be applied by way of a transformer 50 to the anode electrode 6 and the device may be neutralized by a condenser 68. The modulating potentials may be supplied to any circuit by way of coupling condensers 69 and 70.

In the arrangement of Fig. 30, my novel tubes are connected in a novel circuit to produce phase modulation. In this circuit, carrier waves from a carrier wave source are applied by way of a coupling condenser 75 to a phase retarding reactance 1R and to a phase advancing reactance CR in combination with resistances R and R'. The phase shifted oscillations from the reactances 1R and 1C are applied to the accelerating electrodes 4 of the thermionic tubes. Modulating potentials are applied in phase opposition from any source by way of a transformer 77 to resistances R and R' and from said resistances 35 to the accelerating electrodes 4. In the absence of modulating potentials, both tubes supply substantially equal amounts of energy to the anode tank circuit 78 assuming like potentials are applied to the tube electrodes. The energy in 40 78 will have a phase which is the average of the phases of the energies from two tubes. Now assume the tubes are modulated. One tube will supply more energy to 78 than the other. The phase of the energy in 78 will now change and 45 approach the phase of the energy in the output of the tube supplying the most energy to 78. In this manner, phase modulated oscillations are produced in the circuit 78 and may be amplified in the push-pull stage 79 and appear in the tank 50 circuit 80 from which they may be supplied to any utilization circuit. If frequency multipliers are present in the output system the amount of phase deviation will be increased in proportion to multiplication of frequency. The manner in 55 which phase modulation is accomplished is set forth more in detail in my U. S. application, Serial No. 611,050, filed May 13, 1932 now Patent #1,999,902 dated April 30, 1935.

In the arrangement of Fig. 31, the tube may 60 act as a detector or converter for keyed or modulated currents supplied from the transformer 70 to the accelerating electrode 4. The amplified energy appears in the windings of transformer 76 and are applied in push-pull relation to the 65 accelerating electrodes 4 of a pair of tubes 71. These tubes have their anode currents controlled by the tone currents and impress energy characteristic thereof on resistors 78 and 79 connected with the anodes. If the input from 70 is 70 a keyed tone signal, such as used to transfer messages over wire lines, then the circuit shown may be made to have a reversing direct current output, the polarity of which will depend upon whether the signal is on or off. The reversing 75

direct current output may be fed to any apparatus for use in a repeating or recording system. This sort of arrangement is often needed to operate keying relays, signal recorders, etc. An on-off output, without reversing of polarity, may be obtained by using a single tube in the stage 11.

In Fig. 31a I have shown means for impressing signals of any type, as for example, keyed tone oscillations or high frequency oscillations for transmission. The keyed tone signals may be impressed on the accelerating electrode 4 and cathode 2 of the tube from any source. The tube acts as a rectifier and rectified impulses characteristic of the signals are impressed by way of the modulation transformer 16 onto a modulation transformer MT onto a modulator and from said modulator onto an amplifier A and from the amplifier to a load circuit. Carrier wave oscillations may be supplied from a source connected as shown to the modulator.

In Fig. 32, I have tubes of the present invention connected in a novel transmitting circuit. This transmitting circuit comprises an oscillation generator 90 in which the accelerating electrode 4 is regeneratively coupled by way of a piezoelectric crystal PC to the tuned tank circuit 92 connected with anode 6 in such a manner that sustained oscillations of a frequency determined by PC are produced when the electrodes are energized. The crystal has another electrode connected to the shielding and accelerating electrode 9. The shielding between the anode electrode and circuit and the accelerating electrode and circuit afforded by 9 may be supplemented by a screen S arranged as shown. The electrode 4 may be charged with a positive potential by way of a resistance 93. The oscillations appearing in 92 are transferred by way of a lead 94 to the accelerating electrode 4' of an amplifier stage 96 wherein they are amplified and appear in the tuned tank circuit 98 connected with the anode 6' from which they are supplied in push-pull relation to the accelerating electrodes 4'' of a pair of power amplifiers or modulators in an amplifying and modulating stage 100. The modulating potentials are supplied from a transformer 95 to the accelerating electrode 101 of a tube in an amplifier stage 102 and from the anode 103 of said amplifier stage to the accelerating electrode 104 of a tube in the modulator stage 106. This tube has its anode 107 connected to the anodes of the push-pull power stage 100 to accomplish therein anode modulation of the carrier waves. Note here that the use of my novel tube wherein the accelerating electrode may be charged positive permits this electrode to be connected directly to the anode of the preceding tube as in stages 90, 96 and 102, 106. The many advantages flowing from this simplifying of the exciting circuits which permits the anode and accelerating electrodes of adjacent cascaded stages to derive their energy from the same source will be apparent to one skilled in the art.

The stage 96 may operate as an amplifier and as a frequency multiplier. In the latter case, the circuit 98 is tuned at a harmonic of the frequency of the oscillations produced in 90. The modulated oscillations may be impressed on any utilization circuit from the tuned circuit 110 connected with the anodes 9'' of the tubes in the stage 100.

Having thus described my invention and the operation thereof, what I claim is:

1. A vacuum tube or valve, having in combination an elongated cathode lying in the axis of said

tube, an accelerating and focussing control electrode adjacent one end of said cathode and an anode, in which tube or valve the electron current from the cathode to the anode may be varied by varying the potential of the control electrode.

2. A vacuum tube or valve, having in combination a cathode, an accelerating and focussing control electrode, an electron emission element, and an anode arranged in the order recited, a shield electrode adjacent said anode, the division of electron current in said tube to the anode and shield electrode being controlled by varying the potential of the control electrode or shield electrode or both.

3. A vacuum tube according to claim 1, in which electrons leaving different parts of the cathode at one instant of time all arrive at the anode at nearly the same later instant.

4. A vacuum tube according to claim 1, in which said tube has a shield electrode between the anode and control electrode and in which electrons leaving different parts of the cathode substantially all arrive at the shield electrode at substantially the same distance from the axis of the cathode.

5. A tube as recited in claim 2, wherein said anode is fluid cooled.

6. A tube as recited in claim 1, wherein a magnetic field at right angles to the axis of the tube is produced by current flowing in the said cathode to deflect the electrons from said cathode to said anode.

7. A tube as recited in claim 1, wherein the anode is cupped to reduce the effect of secondary emission.

8. A tube as recited in claim 2, wherein the anode is cupped to reduce secondary emission and said anode is fluid cooled.

9. In an electronic system, an elongated emission element which when energized emits electrons radially from the axis thereof, an accelerating electrode located adjacent one end of said emission electrode, and an anode located adjacent one end of said emission element, different points on the surface of said anode being different distances from said emission element.

10. A thermionic discharge device comprising an electron system including an emission electrode, an accelerating electrode adjacent thereto, and an anode adjacent said emission electrode and an additional electron collecting electrode adjacent said anode on which electrons may fall when the accelerating electrode is properly charged whereby the polarity of potentials on the anode may be reversed relative to the polarity of potentials applied to the accelerating electrode.

11. A thermionic discharge device comprising an electron system including an emission electrode, an accelerating electrode, an anode, and a plurality of collecting electrodes on opposite sides of said anode on which electrons may fall when the accelerating electrode is properly charged whereby the potentials on the anode may be in phase or out of phase relative to potentials applied to the accelerating electrode.

12. In an electron discharge device, an elongated cathode element which when energized emits electrons radially of the axis thereof, an anode located adjacent one end of said emission element, an accelerating electrode adjacent the other end of said cathode, points on the surface of which are located at different distances from said emission element, and means for energizing said accelerating electrode to thereby concentrate said electrons in a narrow path along the

- axis of said cathode which path may be varied radially whereby a large amount of current conversion may be obtained.
13. In an electron discharge device an elongated emission element, an anode located adjacent one end thereof, means for energizing said emission element whereby electrons are emitted radially therefrom and driven toward said anode by the magnetic field produced by energizing current in said emission element, means for accelerating the travel of said electrons toward said anode comprising an accelerating electrode mounted adjacent the other end of said emission element, and means for energizing the same to produce an electric field.
14. In an electrical discharge device, means for producing a diffused electron emission, an anode, and means for imparting different rates of acceleration to the electrons of said emission whereby substantially all of the electrons leaving the first means at a particular instant reach the anode simultaneously or at the same later instant.
15. In an electrical discharge device, means for producing a diffused electron emission; an anode at one side thereof, and an accelerating electrode at the other side of said means for imparting different rates of acceleration to the electrons of said emission to cause substantially all of the electrons leaving the first means at a particular instant to reach the anode at the same later instant.
16. In an electrical discharge device an elongated electron emission member, a cup shaped accelerating electrode adjacent one end thereof and a fluid cooled anode having a curved surface located adjacent the other end thereof.
17. In an electrical discharge device an elongated electron emission member, a cup shaped accelerating electrode adjacent one end thereof, an anode, a cross section of which is U-shaped located adjacent the other end thereof, and a shielding and accelerating electrode interposed between said anode and said member.
18. An electrical discharge device comprising, an elongated heavy current cathode member, a cup shaped accelerating control grid at one end of said cathode, a fluid cooled anode coaxially located with respect to said cathode at the other end thereof, and a shield member connected to said cathode and interposed between said cathode and said anode.
19. An electrical discharge device comprising, an elongated heavy current cathode member, a curved annular accelerating control grid coaxially located at one end of said cathode, and a ring shaped anode coaxially located with respect to said cathode at the other end thereof.
20. A system comprising an electrical discharge device having elongated linear means for producing emission of electrons, a charged member adjacent one end of said linear means having a continuous surface the distance of different points on which from said means varies whereby the acceleration imparted to the electrons from said means decreases as the distance between said means and member increases, and an anode adjacent the other end of said elongated linear means.
21. An electrical discharge device comprising an elongated heavy current cathode member, a curved annular shaped accelerating control grid located at one end of said cathode, said grid's axis being on the axis of said cathode, and an anode having a non-planar surface coaxially located at the other end of said cathode.
22. An electrical discharge device comprising, an elongated heavy current cathode member, a cup shaped accelerating and control grid electrode at one end of said cathode, a circular anode having a U-shaped cross section at the other end of said cathode, and a shield member connected with said cathode and interposed between said cathode and said anode, there being openings in said shield member to permit the electrons leaving said cathode to reach said anode.
23. An electrical discharge device comprising, an elongated heavy current cathode member, a curved annular accelerating and control grid electrode at one end of said cathode, an anode at the other end of said cathode, a shield member connected with said cathode and interposed between said cathode and said anode, and a second shield member conductively connected to said cathode and located on the side of said anode remote from said cathode.
24. An electrical discharge device comprising, an elongated heavy current cathode member, a cup shaped accelerating and control grid located adjacent one end of said cathode, a radially expanded shield member connected to the other end of said cathode, said shield member extending back along said cathode to enclose the same, and a shell-like anode located at the other end of said cathode.
25. A thermionic tube comprising, an elongated cathode which when heated tends to produce radial emission, a cup shaped accelerating and control grid coaxially mounted at one end of said cathode to produce when charged longitudinal deflection of said emission; an anode of a U shaped cross-section located at the other end of said emission element, and means to permit only a concentrated stream of electrons to reach said anode.
26. An electron discharge system comprising, a cathode member, an accelerating and control electrode located adjacent one side of said cathode member, and an anode located at the other side of said cathode member.
27. A thermionic tube comprising a cathode, including an elongated electron emission portion one end of which terminates in a shield portion, an accelerating and control grid coaxially mounted at one end of said elongated emission portion, and an anode coaxially located at the other end of said cathode emission portion adjacent said shield portion.
28. A discharge device comprising an elongated cathode from which emission takes place, an accelerating electrode located at one end of said cathode, an anode located at the other end of said cathode, and means for applying potentials to said accelerating electrode cathode and anode such that the distance traveled by each electron emitted from said cathode to said anode times the rate of travel is equal to a constant.
29. A relay system comprising an electrical discharge device having elongated means which when heated produce diffused emission of electrons, a control member, a circuit including a source of direct current between said means and member, said member being adjacent one end of said means and having a surface the distance of which from said means varies whereby the acceleration imparted to the electrons by said member decreases as the distance between said means and member increases, and a circuit connected between said means and said member for

superimposing varying potentials on said direct current potentials.

30. A signalling system comprising an electrical discharge device, means for producing a diffused electron emission, an anode, means for imparting different rates of acceleration to the electrons of said emission whereby substantially all of the electrons leaving the first means at a particular instant are concentrated on the anode 10 at the same later instant, means for applying varying potentials to said second means, and an output circuit connected between said first means and anode.

31. In an amplifier system, an electrical discharge device having elongated means which when heated produce diffused emission of electrons, a heating circuit connected with said means, a control member, an alternating current circuit and a source of direct current connected between said means and member, said member being adjacent one end of said means and having a surface the distance of which from said means varies whereby the acceleration imparted to the electrons by said means decreases as the distance between said means and member increases, an anode located at the other end of said means, an alternating current circuit and a source of potential connected between said means and said anode, and an additional electrode interposed 30 between said means and anode for limiting the path between said means and anode.

32. In an amplifying system, a pair of electrical discharge devices each having means for producing a diffused electron emission, an anode, an electrode for imparting different rates of acceleration to the electrons of said stream whereby substantially all of the electrons leaving the first means at a particular instant are concentrated on the anode at the same later instant, and an electron stream limiting electrode between said means and anode, an alternating current circuit connecting said accelerating electrodes in push-pull relation, said circuit being connected to said means, and an alternating current circuit coupling said anodes in push-pull relation, said last named circuit being also connected to said means.

33. A system as recited in claim 31 in which the potentials applied to said additional electrode and said anode are such that the fluctuating potentials on said additional electrode add to the potential fluctuations on said anode to produce regeneration.

34. A system as recited in claim 31 in which said alternating current circuit and source of potential between said means and said anode is also connected to said additional electrode.

35. In a demodulator system, an electrical discharge device having elongated means which when heated produce diffused emission of electrons, a control member located at one end of said elongated means, a circuit including a source of direct current between said means and member, said source of direct current being sufficient 60 to produce rectification of wave energy in said device, a circuit for applying potentials to be rectified to said control member, said control member having a surface the distance of which from said means varies whereby the acceleration imparted to the electrons by said means decreases as the distance between said means and member increases, an anode located at the other end of said means, and an alternating current circuit including a source of potential connected between 70 said means and anode.

36. A demodulator system as recited in claim 35 in which an additional electron stream path limiting means is interposed between said means and said anode and connected to said last named source. 5

37. A system as recited in claim 35, in which an additional source of waves is coupled to said second named circuit.

38. A system as recited in claim 35, in which an additional electrode is connected with said last named circuit and source and interposed between said means and said anode. 10

39. A system as recited in claim 35, in which said second named circuit is coupled to said last named circuit to produce regeneration in said device and circuits. 15

40. In a modulator system, an electrical discharge device having an elongated emission element, an accelerating electrode at one end of the emission element and an anode at the other end of the emission element, means for applying carrier wave oscillations to be modulated to said accelerating electrode, a utilization circuit connected with said anode, and a source of modulating potentials coupled to one of said electrodes. 20 25

41. A modulating system as recited in claim 40 wherein said tube includes a shielding and accelerating electrode between said anode and said emission element, and wherein said source of modulating potentials is connected to said anode 30 and to said shielding and accelerating electrode.

42. In a phase modulation system, a pair of thermionic tubes each having an elongated emission element, an accelerating electrode located adjacent one end of said emission element, an anode located adjacent the other end of said emission element, and a shielding electrode mounted between said anode and said cathode, a source of high frequency oscillations, phase shifting reactances coupling said source of high frequency oscillations to the accelerating electrodes in said tubes, a source of modulating potentials, a circuit connecting said source of modulating potentials in phase opposition to the accelerating electrodes in said tubes, and a utilization circuit connecting the anodes of said tubes in push-pull relation. 40 45

43. In an electron discharge device, an elongated linear emission element which, when energized, produces an electron emission radially with respect to the axis thereof, an accelerating and focussing electrode located at one end of said emission electrode to concentrate said radially emitted electrons in a stream along the axis of said electron emission element and a collecting 50 55 electrode located at the other end of said elongated emission electrode.

44. In a wave relaying system, an electron discharge device having emission means which when heated produces diffused emission of electrons, a control member, a circuit including a source of direct current between said means and member, said member being adjacent one end of said means and having a surface the distance of which from said means varies whereby the acceleration 60 65 imparted to the electrons by said means decreases as the distance between said means and member increases, means for applying wave energy to be relayed to said first means and member for superimposing varying potentials on said direct current potential, an anode electrode, an electron stream limiting electrode between said means and anode, and an output circuit connected between said anode and elec- 70 75

tron stream limiting electrode and to said cathode.

45. In a wave amplifying system a pair of electron discharge devices each having means for producing a diffused electron emission, an anode, and an electrode for imparting different rates of acceleration to the electrons emitted whereby substantially all of the electrons leaving the said means for producing different electron emission at a particular instant are concentrated on the anode at the same later instant, an alternating current circuit connecting said accelerating electrodes together for exciting the same by wave energy in phase, said alternating current circuit being connected to the electron emission means in each device, and an alternating current circuit connecting said anodes in push-pull relation and to the electron emission means in each device.

46. A system as recited in claim 45 wherein each of said devices includes an electron stream limiting electrode between said means and anode and in which means is provided for applying charging potentials to said electron stream limiting electrodes.

47. In a modulation system, an electron discharge device having an elongated emission element, a dish-shaped accelerating electrode adjacent one end of the emission element, an anode electrode adjacent the other end of the emission element, means for applying carrier wave oscillations to be modulated between one of said electrodes and said emission element, a utilization circuit connected between one of said electrodes and said emission element, and a source of modulating potentials connected between one of said electrodes and said emission element.

48. A system as recited in claim 47 wherein an electron stream limiting electrode is arranged between said accelerating electrode and said anode electrode and maintained at a positive potential relative to said emission element.

49. In a modulator system an electron discharge device having an emission element from which diffused electron emission takes place, an accelerating electrode located adjacent one side of said emission element, an anode electrode located on the other side of said emission element, a shielding electrode located between said anode electrode and said accelerating electrode, an alternating current circuit which may be energized by wave energy to be modulated connected with said accelerating electrode and emission element, an alternating current output circuit connected between said anode and shielding electrode and to said emission element and means for applying

modulating potentials to said anode and shielding electrodes.

50. In a modulation system, an electron discharge device having an emission element from which diffused electron emission takes place when said element is energized, an accelerating electrode adjacent said emission element, an anode electrode adjacent the said emission element, said emission element substantially separating said accelerating electrode and anode electrode, a shielding electrode between said anode electrode and emission electrode, a tuned circuit in which alternating current energy may be caused to flow connecting said shielding electrode to said emission element, means for applying a potential to said accelerating electrode relative to said emission element, an alternating current output circuit connected between said anode and said emission element, said output circuit being coupled to said tuned circuit, and means for applying modulating potentials to said anode electrode.

51. In a modulation system, an electron discharge device having an emission element from which diffused emission takes place when the element is energized, an accelerating electrode, an anode electrode, said accelerating electrode and anode electrode being substantially separated by said emission electrode, a shielding electrode between said anode electrode and said accelerating electrode, frequency stabilizing means connecting said accelerating electrode to said emission element, a tuned circuit in which wave energy to be modulated may be caused to flow connected between said shielding electrode and said emission element, an alternating current circuit connected between said anode electrode and said emission element, said alternating current circuit being coupled to said tuned circuit, and means for applying modulating potentials to said anode electrode.

52. In a modulation system, a source of oscillations to be modulated, a load circuit on which modulated oscillations are to be impressed, a modulator connecting said source of oscillations to said load circuit, and means for impressing modulating potentials from a source of modulating potentials on said modulator comprising, an electron discharge tube having an emission element from which diffused electron emission takes place, a dish-shaped accelerating electrode, an anode electrode, said electrodes being substantially separated by said emission element, means coupling said accelerating electrode to said source of modulating potentials, and means coupling said anode electrode to said modulator.
